(57) **CLAIM**

The ornamental design for a portable blender, as shown and described.

DESCRIPTION

FIG. 1 is a front elevation view of a portable blender, shown without the base for ease of illustration, showing my new design;

FIG. 2 is a rear view thereof, shown without the base for ease of illustration;

FIG. 3 is a left-side view thereof, shown without the base for ease of illustration;

FIG. 4 is a right-side view thereof, shown without the base for ease of illustration;

FIG. 5 is a top plan view thereof, shown without the base for ease of illustration;

FIG. 6 is a bottom plan view thereof, shown without the base for ease of illustration;

FIG. 7 is a front, left and top perspective view thereof, shown without the base for ease of illustration;

FIG. 8 is a front, right and bottom perspective view thereof, shown without the base for ease of illustration;

FIG. 9 is a partially enlarged view thereof, taken from FIG. 3;

FIG. 10 is a partially enlarged view of portion of FIG. 4 thereof, taken from FIG. 4;

FIG. 11 is a front elevation view thereof, shown without the lid for ease of illustration;

FIG. 12 is a rear view thereof, shown without the lid for ease of illustration;

FIG. 13 is a left-side view thereof, shown without the lid for ease of illustration;

FIG. 14 is a right-side view thereof, shown without the lid for ease of illustration;

FIG. 15 is a top plan view thereof, shown without the lid for ease of illustration;

FIG. 16 is a bottom plan view thereof, shown without the lid for ease of illustration;

FIG. 17 is a front, right and top perspective view thereof, shown without the lid for ease of illustration;

(Continued)

FIG. 18 is a rear, left and bottom perspective view thereof, shown without the lid for ease of illustration;

FIG. 19 is a front, left and top perspective view thereof, shown in assembled condition;

FIG. 20 is a front, right and top perspective view thereof, shown in open condition; and,

FIG. 21 is a partially enlarged view thereof, taken from FIG. 20.

The dot-dash broken lines of FIGS. 3, 4, 9 and 10, 20, 21 are included to show the partially enlarged views only and form no part of the claimed design.
